GARMENT COVER AND HANGER ASSEMBLY

Peter P. Petrunya, McKees Rocks, Pa.

Application June 26, 1956, Serial No. 593,895

1 Claim. (Cl. 53—241)

This invention relates to a garment cover and hanger assembly and, more particularly, to an improved shape for garment covers for enabling them to be nested to form a bundle and supported at an appreciable height so that, thereafter, they may be individually pulled down over a garment suspended underneath.

In dry cleaning establishments, the usual practice in covering a cleaned garment, such as a coat, with a paper cover or wrapper, is to first hang the garment on a hanging rod and then to lift a cover on the rod by sliding its top opening therealong and then suspend the clothes hanger on the hook at the lower portion of a hanger rod, and thereafter to lower the paper cover onto the hanger and garment so as to protect the garment against soiling as it is being carried home, by the customer, from the dry cleaning establishment.

This system has outstanding disadvantages in that each time a garment cover is to be used, the cover must be first lifted on the hanger rod, and thereafter pulled down. Furthermore, each paper cover must be individually handled and separately stored, such as underneath a counter. The conventional paper cover is of substantially rectangular shape, that is, the sides extend in vertical, parallel relationship, therefore, such covers cannot be assembled in nesting relationship.

In accordance with an object of my invention, the paper cover for the garment is made of a different shape than the conventional one, that is, the sides are slightly tapered downwardly and outwardly, rather than being parallel, as are the shoulder covering portions. Thus the garment covers may be easily nested together so that a large bundle of garment covers can be nested together and supported in bundle form at a substantial height. Thus all that the attendant has to do is to support the garment hanger 14 on the hanger eye 12 and merely pull down the innermost cover in the bundle, thus tearing it from its support.

Another object of my invention is to provide a novel hanger or support for nested paper covers for garments, whereby the covers are held in a bundle at a substantial height, and including a hook or eye, lowermost, for supporting a hanger on which the garment is mounted.

Other objects and advantages of the present invention will become apparent from a study of the following description taken with the accompanying drawing, wherein:

Figure 1 is a front view of a novel hanger for nested garment covers, embodying the principles of my invention, and showing a supporting hook in the operative position;

Figure 2 is a front view similar to Figure 1 except that it shows the supporting hook retracted within the tube, which is the initial position before the nested paper covers are pierced by the supporting hook;

Figure 3 is a side view of the hanger shown in Figures 1 and 2;

Figure 4 is a side view of the hanger and supported, nested garment covers;

2

Figure 5 is a front view of the assembly shown in Figure 4;

Figure 6 shows a blank for forming one of the paper covers for a garment; and

5 Figure 7 is a front view of one of the paper covers for the garment in completed form.

Referring more particularly to Figures 1, 2 and 3 of the drawing, which shows a hanger forming part of the assembly embodying the present invention, numeral

10 1 denotes a hollow tube having a longitudinally extending slot 2 adjacent the top portion thereof and having secured to the inner wall of the upper end thereof, a latch 3. Integrally secured to the lower closed end portion of tube 1 is a hollow cylindrical boss 4 enclosing a helical spring 5 which is compressed by means of outwardly extending pins 6 integrally formed on rod 8 and projecting through slots 7 of the hollow cylindrical element 4. Rod 8 is slidably mounted inside of tube 1 and boss 4. A sharp supporting hook 9 is pivotally mounted by a pin 10 on the rod 8. A latch element 11 is integrally formed on the upper portion of rod 8. An eye 12 is integrally formed on the lower end of rod 8 which serves as a support for a clothes hanger 14.

20 Turning now to Figures 4 to 7 inclusive, it will appear

25 that the paper covers 21 for the garments are of substantially trapezoidal shape, that is their sides 21a are downwardly and outwardly inclined, as well as their shoulder portions 21b. As shown more clearly in Figures 6 and 7, each cover may be made from a single blank having 30 the outline shown in Figure 6, which is thereafter glued along flaps 21c so as to form a cover having the shape shown in Figure 7. An alternative method is to take a conventional, rectangular shaped cover and merely fold the upper edge along a diagonal line to provide a taper 35 shown along edge 21a.

In view of the slight downward and outward taper of the cover 21, a large number of such covers may be placed in nested relationship, as shown in Figure 5, and then held together as a bundle by projecting the sharp

40 supporting hook so as to form holes 24 adjacent the upper edges of the covers. Initially the tube 1 is projected through the nested covers with the hook 9 in the retracted position as shown in Figure 2. When so retracted it compresses spring 5 and is maintained in the latching position by the latch elements 3 and 11, as shown. When it is desired to unlatch elements 3 and 45 to pierce the nested covers by hooks 9, eye 12 is turned through an angle of 90° so as to unlatch element 3 and allow the hook 9 to project outwardly of tube 1 under the action of spring 5, as illustrated in Figure 1 so as 50 to pierce holes 24 at the top of covers 21 so as to support them as a bundle.

In operation, the operator will hang a garment by 55 placing hanger 14 on eye 12, and thereafter will grasp the innermost paper cover 21 and pull it down over the hanger 14 by making a tear between hole 24 and the upper edge of the cover by means of hook 9. Thus each time another garment is to be covered, this action is 60 repeated, that is, the innermost paper cover is pulled downwardly and torn away from its supporting hook 9.

In view of the nested relationship of the paper covers, the portions thereof corresponding to the positions of holes 24 are disposed along a slight angle which is the 65 reason for disposing the supporting hook 9 along the corresponding angle shown in Figure 1. Thus a large number of covers may be stored overhead instead of taking up counter space, and without the necessity of raising a cover each time a garment is to be covered.

70 Thus it will be seen that I have provided an efficient shape of paper cover for garments so as to permit the covers to be nested in the form of a large bundle. Also

I have provided a novel supporting rod assembly including a retractable hook which is adapted to pierce the top edge of each garment cover, so that the operator need only hang the garment underneath the supporting rod and pull the innermost cover away from the supporting hook and onto the garment. Furthermore, I have provided a garment cover assembly that enables a considerable savings of time on the part of personnel in dry cleaning establishments.

While I have illustrated and described an embodiment of my invention, it will be understood that this is by way of illustration only, and that various changes and modifications may be made within the contemplation of my invention and within the scope of the following claim.

I claim:

A garment cover support assembly comprising a vertically disposed, hollow cylindrical tube, a rod extending axially throughout the entire length of said tube and projecting from the end portions thereof, a supporting

element secured to the lower end of said rod, a supporting hook pivotally mounted on said rod and swingable angularly outwardly from the upper portion of said rod through a longitudinal slot in said tube, spring means surrounding said rod within said tube for normally urging said rod upwardly and said hook outwardly of said tube, and latching means for maintaining the spring under compression when said rod is pulled downwardly resulting in retraction of said hook within said tube by virtue of the bearing point for the hook provided at the lower end of said tube slot.
